[57] CLAIM

The ornamental design for a spray gun body, as shown and described.

DESCRIPTION

FIG. 1 is a side view of a spray gun body showing my new design, the other side being a mirror image;

FIG. 2 is a top view of the spray gun body of FIG. 1;

FIG. 3 is a bottom view of the spray gun body of FIG. 1;

FIG. 4 is a back view of the spray gun body of FIG. 1; and,

FIG. 5 is a front end view of the spray gun body of FIG. 1.

The broken line showing is for illustrative purposes only and forms no part of the claimed design.

FIG. 5

FIG. 1

FIG. 2

FIG. 3

FIG. 4
